UNITED STATES PATENT OFFICE.

OLE T. PRESTHOLDT, OF CLARKFIELD, MINNESOTA.

DESIGN FOR A MEDAL OR SIMILAR ARTICLE.

SPECIFICATION forming part of Design No. 29,812, dated December 20, 1898.

Application filed October 27, 1898. Serial No. 694,751. Term of patent 3½ years.

To all whom it may concern:

Be it known that I, OLE T. PRESTHOLDT, a citizen of the United States, residing at Clarkfield, in the county of Yellow Medicine and 5 State of Minnesota, have invented a new and original Design for a Medal or Similar Article, of which the following is a specification.

This invention relates to a new and original design for a medal or similar article; and 10 it has for its object to provide a design of this character that shall be both useful and ornamental.

The leading feature of the design resides in a body provided on one side thereof with a 15 scene representing the conventional national figure of Uncle Sam in the act of feeding a hen and brood of chickens and also having an arm uplifted in the act of shooting a hawk, while in the background appears the representation of a battle-ship, the said body being 20 provided on the side opposite the scene with a group of the heads of men of national reputation.

A minor feature of the design is having the 25 body of a circular shape.

In the drawings, Figure 1 is a plan view of the obverse side of a medal or similar article embodying a portion of the design contemplated by the present invention. Fig. 2 is a 30 similar view of the reverse side of the article, showing the remaining portion of the design.

Referring to the accompanying drawings, the numeral 1 designates a circular body provided on the obverse side or face 2 thereof 35 with a scene representing the conventional

national figure of Uncle Sam standing on a strip of land and shown in the act of feeding a hen and a brood of chickens with one hand, while the other hand is uplifted and grasps a firearm in the act of shooting a hawk hovering above the brood of chickens. In the background appears a stretch of water with the representation of a battle-ship, and the entire picture is symbolical of the late war between the United States and Spain. In 45 carrying out the thought of the picture the hen and brood of chickens are intended to symbolize the Cubans and rising generation of Cuba, while the hawk is symbolical of Spain, and the battle-ship is intended to be 50 symbolical of the destroyed United States battle-ship Maine.

On the obverse side 3 of the body the latter is provided with a group of the heads of men of national reputation who have figured 55 prominently in said war with Spain—such, for instance, as President William McKinley, Admirals Dewey, Sampson, and Schley, and Generals Miles, Merritt, and Shafter.

What is claimed is—

The design for a medal or similar article herein shown and described.

In testimony that I claim the foregoing as my own I have hereto affixed my signature in the presence of two witnesses.

OLE T. PRESTHOLDT.
